New York, N. Y., a corporation of New York

Application November 18, 1939, Serial No. 305,082

7 Claims. (Cl. 58—26)

This invention relates to corrective time controlled systems and more particularly to improvements in secondary apparatus for use in such a system, and it has for a general object to provide apparatus of this type which is of improved construction and arrangement of parts.

A further object is to provide a secondary apparatus of the type including a plurality of time indicating elements and including an improved means for controlling the reception of periodic normal and corrective impulses from a master clock.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a section through the stamp just inside the print head taken on line 1—1, Fig. 3.

Fig. 2 is a sectional view through the printing wheels taken on line 2—2, Fig. 1.

Fig. 3 is a top plan view of the stamp with the cover broken away for clearness.

Fig. 4 is a wiring diagram showing the circuits of the master clock for sending minute impulses and corrective impulses to the time mechanism of the time stamp.

Fig. 5 is a graphic representation of the cams on the units of minute and tens of minute wheels.

Fig. 6 is a detail view of the cams which control the transfer contacts and their feelers.

The improved form of secondary apparatus comprising the present invention is shown in the drawings as advantageously embodied in a time stamp. The time stamp comprises a base 21 in which is pivotally mounted a platen 22 and to which is pivoted at 23 an arm 24. This arm comprises two parts suitably secured together by cross members.

Referring to Fig. 2, a shaft 25 supported in bosses extending inwardly from the sides of the arm 24 supports a plurality of type wheels identified as the units of minutes wheel 26, tens of minutes 27, hours 28, day 29, month 30 and year 31. A gear 32 is mounted adjacent to the units of minutes wheel 26 and is secured thereto by a clip 33 so that the gear 32 and wheel 26 rotate in unison.

In order to advance the gear 32 and units of minutes wheel 26 a disc 34 is secured on a hub 35 which is mounted to oscillate on a projection 36 which extends inwardly from the frame and in which the shaft 25 is mounted. A link 37 (Figs. 55

2 and 3) connects the disc 34 to an armature 38 of a magnet 39 and a spring 40 normally holds the parts in the positions in which they appear in Figure 1, with a projection of the link against a stop 41. Energization of the magnet 39 rocks the armature 38 clockwise (Fig. 1) drawing the link 37 toward the right and rocking the disc 34 counterclockwise. When the magnet 39 is de-energized, the spring 40 restores the link 37, armature 38 and the disc 34 to their normal positions.

The oscillatory movement of the disc 34 is utilized to advance the units of minutes wheel 26. The magnet 39 is energized once each minute in a manner hereinafter set forth and consequently actuates the disc 34 once per minute.

A spring-pressed pawl 42 pivotally carried on the disc 34 cooperates with a pinion 43 supported on a stud 44 projecting inwardly from the arm 24. The pinion 43 also meshes with the gear 32. Every other tooth of the pinion 43 is cut off opposite the disc 34 and this disc is provided with a tooth space or notch 45.

During the counter-clockwise movement of the disc 34 the pawl 42 wipes by the pinion 43, the disc 34 locking the pinion against rotation. When the disc 34 is rotated clockwise the nose of the pawl 42, being slightly in advance of the notch 45, engages the pinion 43 rotating said pinion counter-clockwise. During this movement the notch 45 engages the next tooth on the pinion 43 completing the two space rotation thereof. This advances the gear 32 and units of minutes wheel 26 two teeth or one type space.

Transfer is effected between the type wheels 26 and 27, 27 and 28, and 28 and 29 by Geneva transfer pinions 6, 7, and 8, respectively (Fig. 2). The pinions are mounted on brackets 9, 10, and 11, respectively, supported between the shaft 25 and a rod 52 mounted in a bar 53 extending between and secured to the sides of arm 24. The month and year wheels 30 and 31, respectively, may be manually set, there being no transfer provided from the day wheel 29 to the month wheel 30. Such transfer mechanism may, however, be easily provided. The bar 53 carries a printing plate 53a to print data other than that printed by the type wheels.

The manner in which the time stamp is used will be apparent to those skilled in the art. When it is desired to stamp the date and time on a sheet of paper, or other object, the paper is inserted between the arm 24 and platen 22, and the arm 24 then manually depressed to effect the impression on the paper of the date and time

manifesting type carried by the wheels 26 to 31, inclusive, which are then in printing position. The usual inked ribbon 46 is disposed between the type and paper and effects the printing in the well known manner.

In the diagram (Fig. 4) there is shown a master clock which may be of any conventional type with the usual time train which drives a minute arbor 96 causing said arbor to make one rotation per hour. There are two cams 97 and 98 on this arbor, the cam 97 controlling contacts 99 and the cam 98 controlling contacts 100. The contacts 100 close 50 seconds before the hour or before the 60th minute and open 20 seconds before the 60th minute. The contacts 99 close 10 minutes and 10 seconds before the 60th minute and open 10 seconds before the 60th minute. The time train also drives a minute cam 101 which actuates minute contacts 102. The usual verge or escapement 103 operates rapidly acting contacts 104. Relays 105 and 106 when energized operate contacts 107 and 108, respectively.

Normal impulses are transmitted from the battery "B" over contacts 102 which close once per minute through relay 105 and back to the battery "B." Energization of relay 105 closes contacts 107 so that impulses flow from battery "B" over line 111 to the secondary, through magnet 39 (see also Figs. 1 and 3), contacts 109, contacts 107 to battery "B." Energization of the magnet 39 (Figs. 1, 3, and 4) advances the units of minutes type wheel one space as previously described. When the contacts 100 close at 50 seconds before the 60th minute more rapid impulses are sent by the contacts 104 to the relay 105. The rapidly repeated energization of this relay sends a plurality of successive impulses to the secondary for the purpose of advancing the time mechanism of any secondaries which are slow.

The secondary referred to above, comprises the magnet 39 (Figs. 1, 3, and 4), the time wheels or type wheels 26 to 31, inclusive, and the mechanism whereby the magnet 39 advances the type wheels.

To control the reception of the impulses in the secondary transfer contacts 109 and 110 (Figs. 1, 3, and 4) are provided under the control of the units of minute type wheel 26 and the tens of minute wheel 27. Reference to Figure 3, discloses that these wheels have cam grooves formed in their peripheries. Figure 5 graphically indicates these grooves and Figure 6 shows the profile of the actual cams. A feeler 112 (Fig. 6) pivoted on the rod 52 cooperates with the cam on the units of minutes wheel 26 and a feeler 113 also pivoted on the rod 52 and rigidly connected to the feeler 112 by a yoke 114 cooperates with the cam on the tens of minutes wheel 27.

Extending upwardly from the feeler 112 is an arm 115 having pivoted to its upper end a link 116 through the opposite end of which link projects the center contact of the transfer contacts 109-110.

The cams cooperating with the feelers 112 and 113 are so shaped that the feelers and the arm 115 are held in the position indicated in Figure 6 in connection with the showing of the tens of minutes wheel 27. This through the link 116 holds the contacts 109 closed until the 59th minute when both feelers 112 and 113 drop into the low position of their receptive cams under the influence of the spring tension of the center contact. This opens contacts 109 and closes contacts 110. At 5 minutes past the hour the feel-

ers 112 and 113 are cammed out opening contacts 110 and closing contact 109.

Those secondaries which are on time or which are in synchronism with the master clock or those which are fast when they arrive at the 59th minute open contacts 109 and close 110 and are thus unaffected by the corrective impulses which start when contacts 100 close 50 seconds before the 60th minute because the contacts 99 closed at 10 minutes and 10 seconds before the 60th minute energizing magnet 106 and opening the contacts 108. At ten seconds before the 60th minute the contacts 99 open permitting contacts 108 to close so that the 60th minute impulse is transmitted over the contacts 107, contacts 108, contacts 110 now closed to energize the magnet 39 which advances the units of minutes wheel 26 to the zero position. At this time a transfer is effected from the units of minutes wheel 26 to the tens of minutes wheel 27 advancing the latter also to zero position. Transfer is also effected at the same time between the tens of minutes wheel 27 to the hour wheel 28 advancing this wheel to the next hour.

25 The secondary or secondaries which are slow have not shifted the contacts 109-110 at the time the correction impulses are transmitted by contacts 104. Consequently these impulses through relay 105 repeatedly close contacts 107 which send impulses over contacts 109 to the magnet 39 until the secondary clock which is slow arrives at the 59th minute when contacts 109-110 shift. The contacts 108 being open at this time no further impulses are received by magnet 39 until the 60th minute impulse is sent as described above.

30 While there has been shown and described and pointed out the fundamental novel features of the invention as applied to a single modification 40 it will be understood that various omissions and substitutions and changes in the form and details of the device illustrated and in its operation may be made by those skilled in the art without departing from the spirit of the invention. It is 45 the intention, therefore, to be limited only as indicated by the scope of the following claims.

What is claimed is:

1. In a secondary apparatus for use in a corrective time controlled system, a plurality of time 50 indicating elements, an impulse magnet to receive periodic impulses from the corrective time system for normally advancing said indicating elements at a rate to indicate correct time, sensing means for determining the positions of said elements, and means controlled by the sensing means and operated conjointly by a plurality of the indicating elements to control the reception of said impulses by said magnet.

2. In a secondary apparatus for use in a corrective time controlled system, a plurality of time indicating elements, an impulse magnet to receive periodic impulses from said system for normally advancing said elements and also to receive corrective impulses from said system, and 60 mechanical position sensing means conjointly operated by two of the time indicating elements when said elements are in predetermined chronological positions for controlling the reception of both classes of impulses by said magnet to effect synchronization between said apparatus and said system.

65 3. In a secondary apparatus for use in a corrective time controlled system wherein time control is effected by periodic impulses originating from a master clock, the combination of a plu- 70 75

rality of time indicating wheels, a drive motor adapted to be energized by the master clock impulses, drive mechanism connected to said motor and operable to advance the indicating wheels at predetermined rates which are proportional to the rate at which impulses are received by said motor so as normally to cause said wheels to indicate the correct time of day, a cam integral with each of said wheels for movement therewith, and means conjointly controlled by a plurality of said cams for superseding the normal master clock control of the operation of the drive motor, thereby to effect synchronization between said apparatus and said system.

4. In a secondary apparatus for use in a corrective time controlled system wherein time control is effected by periodic impulses from a master clock, the combination of a plurality of denominational order time manifesting elements, a drive motor adapted to be energized by the master clock impulses, drive mechanism connected to said motor for advancing the lowest order element a predetermined amount for each energization of the motor so as normally to cause said elements to indicate the correct time of day, a plurality of cam members individually associated with the manifesting elements and synchronized therewith, and means controlled conjointly by the cam member associated with the lowest order element and by another of said cam members associated with another of the time manifesting elements for modifying the master clock control of the operation of the drive motor in the event that the time manifested by said elements differs from that indicated by the master clock.

5. A secondary time unit adapted for use in a master clock impulse-controlled time system comprising, in combination, a plurality of time indicating elements, a drive motor adapted to be energized by periodic impulses from the master clock, drive mechanism connected to said motor and operable to advance the indicating elements at predetermined rates which are proportional to the rate at which impulses are received by said

motor so as normally to cause the elements to indicate correct time, sensing means for sensing the positions of said elements, and means operated by the sensing means according to the positions of the sensed elements for causing the indicating elements to be operated at a different than normal rate in accordance with the nature of the variance of the time indicated by said elements with the correct time of the master clock.

10 6. A secondary time unit adapted for use in a master clock impulse-controlled time system comprising, in combination, a plurality of time indicating elements, a drive motor adapted to be energized by periodic impulses from the master clock, drive mechanism connected to said motor for advancing the time indicating elements, regulating means for said elements including a plurality of cams, each individually connected with one of the elements for movement therewith, and means controlled conjointly by said cams and effective at predetermined intervals to modify the master clock control of the drive motor.

25 7. In a secondary apparatus for use in a corrective time controlled system wherein time control is effected by periodic impulses from a master clock, a plurality of movable time indicating elements, a drive motor adapted to be energized by said impulses from said master clock, drive mechanism connected to said motor and operable to advance the indicating elements at predetermined rates which are proportional to the rate at which impulses are received by said motor so as normally to cause said elements to indicate by their respective positions the correct time of day, and means controlled conjointly by the respective positions of two of said time elements and operable to modify the normal master clock control of the operation of said drive motor when 30 the time indicated by the position of said elements differs from that indicated by the master clock so that the positions of said elements will be changed to indicate the same time as the master clock.
